C. J. LUCAS ET AL

JOURNAL BOX LID

Original Filed April 30, 1926

FIG. 1.

UNITED STATES PATENT OFFICE.

CHRISTIAN J. LUCAS AND ARTHUR G. PONCE, OF BRACKENRIDGE, PENNSYLVANIA,
ASSIGNORS TO ALLEGHENY STEEL COMPANY, A CORPORATION OF PENNSYLVANIA.

JOURNAL-BOX LID.

Application filed April 30, 1926, Serial No. 105,703. Renewed September 17, 1926.

This invention relates to journal boxes for railway car trucks and more particularly to lids for such boxes and springs for closing the same.

- 5 The standard A. R. A. (American Railway Assn.) journal box for railway car trucks is provided with a lid or cover hinged along its top edge to the box and with a spring by means of which the lid is held 10 in either open or closed position. Various types of springs or spring devices have been suggested for use in this connection, but with those most commonly used, the lid, when in closed position, bears tightly only 15 on the lower box face and stands away varying distances from the side and top box faces. This is necessarily so on account of the construction and operation of this spring.
- 20 Within the last few years, journal box lid closing spring means have appeared and at least one of these provides a self adjusting structure by means of which the lid is caused to bear evenly and tightly on the top, sides 25 and bottom faces which define the journal box opening and this, irrespective of the fit of the lid scrolls on the hinge pin or the fit of the hinge pin within its hole in the box lug.
- 30 The lid and lid closing means to which reference has been made is disclosed in an application for patent filed by Leigh W. Hostettler and employs a torsion spring and a spring tensioning member which is mounted 35 on the hinge pin and bears on the spring on the opposite side thereof from the lid proper.

An object of this invention is to produce a device broadly functioning in the same 40 manner as the device of said Hostettler application, but which is simpler and cheaper for the reason that it avoids the use of a spring tensioning member.

This, as well as other objects which will 45 readily appear to those skilled in this particular art, I attain by means of the structure described in the specification and illustrated in the drawings accompanying and forming part of this application.

50 In the drawings, Figure 1 is an end elevation of a journal box showing this invention in connection therewith and Fig. 2 is a longitudinal sectional view partly broken

away and taken on the line 2—2 of Fig. 1.

In the drawings, the journal box proper 55 is provided with a flat faced top wall 3, a flat faced bottom wall 4 and side walls 5 which also have flat faces and which lie in the plane of the top and bottom walls.

The mouth formed by these walls is rectangular and is inclined as shown, as is now common.

The upper portion of the box proper is projected in the form of a box lug 6 formed with a central spring bearing cammed portion 7 and rounded side portions 8. The cammed portion has two cam faces 7^a and 7^b. The lug is provided with a pin-hole 9 which extends through the same from end to end.

A hinge pin 10 lies within the pin-hole 70 and projects outwardly therefrom beyond each end of the lug 6 to receive the lid scrolls.

The journal box lid is of rectangular outline and is preferably stamped from sheet 75 metal such as steel. The lid chosen for illustration is provided with a depending marginal flange 11 and a finger piece 12 which projects from its lower edge; the lid is stiffened by being embossed as shown.

The lid scrolls 13 project upwardly from the lid body proper and embrace the hinge-pin 10 on opposite sides of the box lug and are so formed as to provide spaces on opposite sides of the box lug or between the 85 ends of the box lug and the lid scrolls.

The scrolls are so formed as to provide substantial clearance between their inner curved surfaces and the hinge pin which they embrace. The clearance is preferably 90 greatest at right angles or perpendicular to the plane of the lid proper or the box face when the lid is in closed position.

The lid is held in closed position by means 95 of the spring which is so formed and so mounted that its closing pressure is applied to the center of the lid whereby the lid is caused to bear evenly over the entire box face, which includes the top, bottom and sides.

The spring is preferably formed from 100 round steel wire and carries an anti-friction roller 15 which bears on one or the other of the cam faces of the box lug depending upon whether the lid is in open or in closed 105 position.

The roller 15 is placed in position at the center of the length of wire from which the spring is made and before the same is bent to form.

5 The spring on opposite sides of roller 15 is provided with two diverging portions 16 preferably formed with a compound curve as shown in Fig. 2. Each of the portions 16 at its lower end is bent into the form of a 10 loop 17 and then extends upwardly on a curve 18 and is coiled around the hinge pin as shown at 19. The coils are closed but fit the hinge pin more or less loosely. From the coils, the spring extends downwardly 15 and is curved as shown at 20 to the ends thereof which are inwardly bent one toward the other as shown at 21, Fig. 1, so as to lie within the depression 22 formed in the lid face for their reception.

20 The ends of the spring are anchored within depression 22 by means of a retaining plate 23 which is secured to the lid by centrally disposed rivets 24.

From the preceding description, taken in connection with the drawings, it will be apparent that the spring device exerts its pressure at the center of the lid and will cause the lid to bear evenly over the entire box face, since there is nothing tending to 25 lift the top of the lid away from the box face. The function of retaining plate 23 is to tie the box lid and spring together when the lid is in open position and when moving from open to closed position.

30 35 From the construction shown, it will be apparent that variations due to inaccuracies in manufacture or those arising from wear of the parts are compensated for, since the device is self fitting.

40 Having thus described our invention, what we claim is:—

1. In a journal box, the combination with the box proper provided with a spring bearing lug and having a lid pivotally connected thereto by means of a hinge pin which extends through the lug, of means for applying a substantially equally distributed yielding pressure against the outer face of the lid near the center thereof, said means comprising a spring element having its ends anchored to the lid, intermediate portions which encircle the hinge pin on opposite sides of said lug and a portion which cooperates with said lug.

45 50 55 60 65 2. In a journal box, the combination with the box proper provided with a spring bearing lug and having a lid pivotally connected thereto by means of a hinge pin which extends through the lug, of means for applying a substantially equally distributed yielding pressure against the outer face of the lid near the center thereof, said means comprising a spring element having its ends anchored to the lid, intermediate portions which encircle the hinge pin on opposite

sides of said lug and a portion carrying an anti-friction roller which bears on said lug.

3. In a journal box, the combination with the box proper provided with a spring bearing lug and having a lid pivotally connected thereto, of means for applying a substantially equally distributed yielding pressure against the outer face of the lid near the center thereof, said means comprising a double bilaterally symmetrical spring, one portion of each half of which is anchored to the lid, intermediate portions which encircle the hinge pin on opposite sides of said lug and a portion which extends from those portions which encircle the hinge pin and which cooperates with said lug.

4. In a journal box, the combination with the box proper provided with a spring bearing lug and having a lid pivotally connected thereto, of means for applying a substantially equally distributed yielding pressure against the outer face of the lid near the center thereof, said means comprising a double bilaterally symmetrical spring with the free end of each half anchored to the lid, intermediate portions which encircle the hinge pin on opposite sides of said lug and a portion which cooperates with said lug.

5. In a journal box, the combination with the box proper provided with a spring bearing lug and having a lid pivotally connected thereto by means of a hinge pin which extends through the lug, of means for applying a substantially equally distributed yielding pressure against the outer face of the lid near the center thereof, said means comprising a double bilaterally symmetrical spring with the free end of each half anchored to the lid, spaced intermediate portions each of which is coiled about the hinge pin and a portion connecting the halves and carrying an anti-friction roller which bears on said lug.

6. In a journal box, the combination with the box proper provided with a spring bearing lug and having a lid pivotally connected thereto by means of a hinge pin which extends through the lug, of means for applying a substantially equally distributed yielding pressure against the outer face of the lid near the center thereof, said means comprising a double bilaterally symmetrical spring with the free end of each half anchored to the lid, spaced intermediate portions each of which is coiled about the hinge pin and a portion which cooperates with said lug.

7. In a journal box, the combination with the box proper provided with a spring bearing lug and having a lid pivotally connected thereto by means of a hinge pin which extends through the lug, of means for applying a substantially equally distributed yielding pressure against the outer face of the lid near the center thereof, said means comprising a spring element having its ends an-

chored to the lid near the center thereof, intermediate portions which encircle the hinge pin on opposite sides of said lug and a portion carrying an anti-friction roller which bears on said lug; the portions of the spring element extending from the ends to the hinge pin being curved away from the lid and the portions extending from the hinge pin to said roller being bent upon themselves.

In testimony whereof, we have hereunto set our names this 19th day of April, 1926.

CHRISTIAN J. LUCAS.
ARTHUR G. PONCE.
